(57) **CLAIM**

The ornamental design for a turbine device for generating electricity from ocean currents, as shown and described.

DESCRIPTION

FIG. 1 is a rear view of a turbine device for generating electricity from ocean currents showing the new design.

FIG. 2 is a front view thereof.

FIG. 3 is a right side view thereof.

FIG. 4 is a left side view thereof; and,

FIG. 5 is a front, right side and top perspective view thereof. The broken lines shown represent unclaimed subject matter and form no part of the claimed design.
